Attorney.

UNITED STATES PATENT OFFICE.

MORRIS P. HOLMES, OF CLAREMONT, NEW HAMPSHIRE, ASSIGNOR TO SULLIVAN MACHINERY COMPANY, A CORPORATION OF MASSACHUSETTS.

MINING MACHINE.

Application filed December 18, 1922. Serial No. 607,536.

My invention relates to mining machines. It has for its object to provide an improved mining machine of the swinging bar type, usually known as the long-wall type, having 5 improved means for unlocking or locking the swinging bar thereof in position before or after a swinging operation. A further object of my invention is to provide improved bar holding means whereby the bar may be 10 automatically locked in position after a swinging operation, and, more particularly, whereby the bar may be moved from its longitudinal position into a lateral cutting position and locked therein automatically as 15 soon as it has completed its movement. These and other objects and advantages of my invention will be hereinafter more fully described.

In the accompanying drawings I have 20 shown for purposes of illustration one embodiment which my invention may assume in practice.

In these drawings,—

Fig. 1 is a plan view of a machine equipped 25 with my improvement, the bar being shown in different positions.

Fig. 2 is an enlarged plan view of the front end of the construction shown in Fig. 1, the bar being shown in longitudinal or 30 transport position.

Fig. 3 is a side elevation of the front end of the machine with parts broken away to facilitate illustration.

Fig. 4 is an enlarged detail transverse sectional view showing the locking pin in and 35 out of locking position.

In this illustrative construction I have shown a mining machine generally designated at 1 slidable on its bottom on a mine 40 bottom and having a pivoted cutter bar 2 carrying a usual circulating cutter chain 3 and adapted to be moved freely about a pivot 4 on the rear end of the machine from the full line longitudinal position shown in Fig. 1 to 45 lateral positions, as for instance the position illustrated in dotted lines in that figure, improved unlocking and locking means for the bar hereinafter described cooperating to lock the bar in the desired position.

50 In my improved construction it will be observed that the head 5 of the mining machine is provided with cut-away portions or notches 6, 7 radially located about the bar pivot and in this illustrative construction in

front and at each side thereof. The bar 2 55 also herein carries an upstanding member 8 having a vertically disposed socket 9 therein adapted to receive a rotary unlocking and locking pin 10, which pin is herein provided with a lateral cut-away portion or transverse slot 11 at a point intermediate its ends and in the plane of the notches 6 and 7, so that the pin may be turned about its axis in such manner as to bring its body portion 12 into the desired one of the notches 6, 7 and 60 65 thereby hold the bar against lateral movement relative to the head, while when the pin is turned reversely the body portion 12 thereof is disposed entirely outside the given notch so that a curved surface 13 on the portion 12 may run along the periphery of the head, indicated at 14, when the bar is swung about its pivot. Attention is also directed to the fact that this pin 10 has a head 15 having a double ended chain slot 16 therein 70 75 disposed perpendicular to its axis and a second communicating chain slot 17 extending from the slot 16 part way around the circumference of the head, these chain slots being provided for cooperation with the flexible feeding member of the machine, herein in the form of a chain 18 and driven with the cutter chain 3 in a well known manner by the mining machine motor through usual connections (not shown).

85 In the operation of my improved construction it will be evident that with the bar in either position illustrated, the pin 10 is rotatable in such manner as to move its body 12 out of its cooperating notch and thus release the bar for swinging movement. When this is done, the flexible feed chain 18 of the mining machine may have its end laid in the slot 16 and its adjacent portion extended 90 around the slot 17 after the fashion shown 95 in Fig. 2 so that after the bar 2 has been moved manually but slightly laterally in such manner that one end of its portion 13 engages with the adjacent end of the surface 14, a pull upon the member 18 will not only swing the bar 2 about its pivot to a position opposite the notch 7, but when the pin 10 is brought opposite the notch 7, rotate the pin 100 reversely in such manner as to bring its body portion 12 into the notch 7 and thereby lock the bar in its adjusted position, whereupon the chain may be manually removed from the recess and lateral cutting begin. Here it 105

will also be noted that after the completion of the lateral cut, when it is desired to swing the bar from the lateral to longitudinal position, it is only necessary to reverse the operation described with the flexible feeding member then being extended reversely around the head in order to swing the bar reversely and lock it in its longitudinally extended position. Attention is also directed to the fact that if desired the bar may be swung laterally to either the right or left as desired and swung back into longitudinal position.

As a result of my improved construction, it will be observed that all necessity for withdrawing a locking pin from the bar and consequent difficulty arising from the effort to dislodge the pin and the difficulty of doing this, especially marked in low coal, is avoided, my improved rotating locking pin being much more readily operable and locking or unlocking the bar without requiring the raising or lowering of any part and consequent digging in the roof or bottom. It will also be evident that the difficult task of locking the bar by inserting a pin is obviated, the rotatable pin being movable into locking position much more readily and quickly in my improved construction. Further, when the flexible feeding member is used, the only steps necessary after the pin has been turned into unlocking position are the connection and disconnection of the free end of the flexible feed member to the top of the pin and operation of the feed to draw in the feed member, steps which may be readily and quickly made. Here it will also be noted that the connection of the flexible feeding member to the pin is maintained after the bar has been locked in its lateral position until manually released, an advantageous feature since the free end of the flexible feeding member is thus prevented from dropping down into the then rotating cutter chain in such manner as to cause damage to the machine.

While I have in this application specifically described this embodiment of my invention utilizing a rotating locking pin as adapted to use with a flexible feeding member in the form of a chain, it will be evident that the pin construction may be modified and also used with other flexible members than chains without departing from the spirit of my invention, it being my intention to include all such modifications within the scope of the appended claims.

What I claim as new and desire to secure by Letters Patent is:

1. The combination with a mining machine having a frame, a swingable cutter bar thereon, and bar swinging means including a flexible connection and guiding means for the latter, of bar locking means automatically operable to lock the bar to said frame after a predetermined swinging movement of the bar,

said bar locking means being operated solely by said flexible connection without changing the relation of the latter with respect to said guiding means.

2. The combination with a mining machine 70 having a frame, a swingable cutter bar thereon, and bar swinging means including a flexible connection and guiding means for the latter, of bar locking means automatically operable to lock the bar to said frame after a predetermined swinging movement thereof in either direction, said bar locking means being operated solely by said flexible connection without changing the relation of the latter with respect to said guiding means. 75

3. The combination with a mining machine having a frame, a swingable cutter bar thereon; and bar swinging means including a flexible connection and guiding means for the latter, of rotary bar locking means automatically operable after a swinging movement of said bar in either direction to lock the latter to said frame, said locking means being operated solely by said flexible connection without changing the relation of the latter with respect to said guiding means. 80

4. The combination with a mining machine having a frame, a swingable cutter bar thereon, and bar swinging means including a flexible member, of bar locking means including a locking member rotatable on its longitudinal axis to lock said bar to said frame, said locking member also forming an abutment for said flexible bar swinging member. 85

5. The combination with a mining machine 100 having a frame, a swingable cutter bar thereon, and bar swinging means including a flexible feeding member, of bar locking means including a locking element rotatable on its longitudinal axis to lock said bar to said frame, said locking member also forming an abutment for said flexible feeding member and being rotatable in one direction by the latter. 105

6. The combination with a mining machine 110 having a frame, a swingable cutter bar thereon, and bar swinging means including a flexible feeding member, of bar locking means including a locking element rotatable on its longitudinal axis to lock said bar to said frame, said locking member also forming an abutment for said flexible feeding member and being rotatable in either direction by the latter. 115

7. The combination with a mining machine 120 having a notched head, a swingable cutter bar thereon, and bar swinging means including a feeding member, of a bar locking pin rotatable on its longitudinal axis and carried by said bar and rotatable into and out of locking 125 engagement with notches in said head, said locking pin also forming an abutment for said feeding member.

8. The combination with a mining machine 130 having a frame, a swingable cutter bar there-

- on, and bar swinging means including a flexible member, or bar locking means including a locking pin rotatable on its longitudinal axis and having provision whereby upon connection of said flexible member to said pin said bar may be swung and said pin rotated to lock said bar to said frame automatically after a predetermined swinging movement of said bar.
- 10 9. The combination with a mining machine having a head provided with radially located recesses and a swinging cutter bar provided with a pin socket therein, of a pin rotatably seated in said socket and having a portion movable into and out of said recesses whereby upon rotation of said pin the bar may be locked in different angular positions, said pin also having a feed member abutment thereon whereby a flexible feed member may be connected thereto to swing the bar.
- 15 10. The combination with a mining machine having a head provided with radially located recesses and a swinging cutter bar provided with a pin socket therein, of a pin rotatably seated in said socket and having a portion movable into and out of said recesses whereby upon rotation of said pin the bar may be locked in different angular positions, said pin also having a feed member abutment thereon whereby a flexible feed member may be connected thereto to swing the bar and after a predetermined movement rotate said pin into locking position.
- 20 11. The combination with a mining machine having a frame, a swingable cutter bar thereon, and bar swinging means including a flexible feeding member, of bar locking means formed on said member and frame including a locking member rotatable on its longitudinal axis and carried on said bar, said locking member having a feed member abutment and arranged after a predetermined swinging movement of said bar relative to said frame to be turned into locking position by said flexible feeding member connected thereto, and to maintain its connection to said flexible feeding member after said turning movement.
- 25 12. The combination with a mining machine having a frame, a swingable cutter bar thereon, and bar swinging means, of bar locking means rotatable on an axis parallel with the axis of bar swing carried by said bar and engageable with said bar swinging means to effect transmission of swinging movement to said bar and automatically movable by said bar swinging means to lock said bar to said frame when a predetermined position is reached.
- 30 13. The combination with a mining machine having a frame and a swingable cutter bar thereon, of bar locking means rotatable on an axis parallel to the axis of bar swing to effect locking of the bar to said frame and means to bias it toward locking position dur-
- ing bar swing whereby said bar may be automatically locked when it reaches a predetermined position.
- 35 14. The combination with a mining machine having a frame and a swingable cutter bar thereon, of bar locking means rotatable on an axis parallel to the axis of bar swing to effect unlocking of the bar from said frame and means to bias it toward locking position during bar swing whereby said bar may be automatically locked when it reaches a predetermined position. 70
- 40 15. The combination with a mining machine having a frame and a swingable cutter bar thereon, of bar locking means including a locking member rotatable on its longitudinal axis to effect locking of said bar to said frame and means to bias it toward locking position during bar swing whereby said bar may be automatically locked when it reaches a predetermined position. 80
- 45 16. The combination with a mining machine having a frame and a swingable cutter bar thereon, of bar locking means including a locking member rotatable on its longitudinal axis in either direction from a predetermined position to effect release of said bar from said frame and means to bias said bar locking means toward locking position during bar swing whereby said bar may be automatically locked when it reaches a predetermined position. 90
- 50 17. The combination with a mining machine having a notched frame and a swingable cutter bar thereon, of bar locking means rotatable on an axis parallel to the axis of bar swing and engageable with the notch in said frame to lock the latter and said bar together and means to bias said bar locking means toward locking position during bar swing 100 whereby said bar may be automatically locked when it reaches a predetermined position. 105
- 55 18. The combination with a mining machine having a frame and a swingable cutter bar thereon, of bar locking means including a locking element rotatable on its longitudinal axis and carried on said bar and engageable with said frame upon rotation in either direction from a predetermined position to lock said frame and bar together and means to bias said element toward locking position during bar swing whereby said bar may be automatically locked when it reaches a predetermined position. 110
- 60 19. The combination with a mining machine having a frame and a swingable cutter bar thereon, of bar locking means rotating on an axis lying in a common plane with the axis of bar swing to change the condition of said bar as respects its being locked to or unlocked from said frame and means to bias said bar locking means toward locking position during bar swing whereby said bar may be automatically locked when it reaches a predetermined position. 120
- 65 130

20. The combination with a mining machine having a frame and swingable cutter bar thereon, of bar locking means carried by said bar and rotatable on an axis lying in a common plane with the axis of bar swing to change the condition of said bar as respects its being locked to or unlocked from said frame and means to bias said bar locking means toward locking position during bar swing whereby said bar may be automatically locked when it reaches a predetermined position.

21. The combination with a mining machine having a frame and a swingable cutter bar thereon, of bar locking means including a locking pin rotatable on its longitudinal axis and having a cut away portion and a body portion movable into locking engagement with said frame and means to bias said locking pin toward locking position during bar swing whereby said bar may be automatically locked when it reaches a predetermined position.

22. The combination with a mining machine having a recessed head and a swingable cutter bar thereon, of a bar locking pin rotatable on its longitudinal axis and carried by said bar and engageable with or disengageable from a recess in said head on rotation in either direction from predetermined positions to lock or unlock said bar with respect to said head and means to bias said locking pin toward locking position during bar swing whereby said bar may be automatically locked when it reaches a predetermined position.

23. The combination with a mining machine having a recessed head and a swingable cutter bar thereon, of a rotary bar locking pin carried by said bar and engageable with or disengageable from a recess in said head to lock or unlock said bar with respect to said head and rotatable on an axis parallel to the axis of bar swing and means to bias said locking pin toward locking position during bar swing whereby said bar may be automatically locked when it reaches a predetermined position.

24. The combination with a mining machine having a frame and a swingable cutter

bar thereon, of bar locking means including a locking pin rotatable on its longitudinal axis to effect locking and unlocking and having a cut away portion and a body portion movable into locking engagement with said frame, said pin having bearing portions at opposite sides of said cut away portion. 55

25. The combination with a mining machine having a frame and a swingable cutter bar thereon, of bar locking means including a locking pin rotatable on its longitudinal axis to effect locking and unlocking and having a cut away portion and a body portion movable into locking engagement with said frame, said locking pin having a bearing 60 portion adjacent said cut away portion and having a portion spaced from said cut away portion by said bearing portion and provided with means whereby a rotating force may be transmitted thereto. 70

26. The combination with a mining machine having a frame and a swingable cutter bar thereon, of bar locking means including a locking pin rotatable on its longitudinal axis to effect locking and unlocking and having a cut away portion and a body portion movable into locking engagement with said frame, said locking pin having a bearing 75 portion adjacent said cut away portion and having a portion spaced from said cut away so portion by said bearing portion and provided with means whereby a rotating force may be transmitted thereto and said pin also having a bearing portion at the opposite side of said cut away portion. 85

27. In combination in a mining machine, a machine frame, a cutter bar pivotally mounted thereon for swinging movement, said frame having an arcuate notched flange and said bar having a lip overlying said flange and supporting means for said lip, and means including a pin having bearing portions above and below said flange and carried on said bar rotatable on an axis parallel to the axis of bar swing into and out of locking engagement with said notched flange. 95

In testimony whereof I affix my signature.

MORRIS P. HOLMES.
